UNITED STATES PATENT OFFICE

JOHN H. PHILLIPS, OF CHICAGO, ILLINOIS

ANCHORING APPARATUS

Application filed May 29, 1925. Serial No. 33,776.

My invention relates to anchoring apparatus and particularly to self-drilling anchoring apparatus. The invention has among its other objects the production of apparatus of the kind described, which is simple, compact, durable, reliable, efficient and satisfactory for use wherever found applicable. A particular object of the invention is to provide improved self-drilling anchoring device which may be employed to drill a relatively large number of holes in concrete, stone or the like and may be readily expanded in one of the holes to serve as an anchor bolt. Another particular object of the invention is to provide an expansible self-drilling anchoring device which will firmly engage the walls of a hole throughout the entire length of the hole after it has been expanded therein. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts;

Fig. 1 is an elevation of an anchoring device embodying the novel features of my invention, the anchoring device being shown in connection with a chuck whereby it may be secured in a spring hammer or the like;

Fig. 2 is a longitudinal section taken through my improved anchoring device, the anchoring device being shown in its expanded condition;

Fig. 3 is an enlarged fragmentary section taken substantially on the same line as Fig. 2, but showing certain features of construction in more detail;

Fig. 4 is a section taken on line 4-4 of Fig. 1;

Fig. 5 is a section taken on line 5-5 of Fig. 4;

Fig. 6 is an end elevation of the improved anchoring device;

Figs. 7 and 8 are sections taken on lines

7-7 and 8-8, respectively, of Fig. 6; and Fig. 9 is a fragmentary elevation of an anchoring device embodying another form of the invention.

In the drawings, 10 is a tubular shell 55 formed of any suitable metal, such as for example case-hardened steel. The shell 10 is provided at one end with drill teeth 16 and 17 and at its other end is collapsed to provide a tongue 19 which comprises superimposed 60 layers of metal. The tongue 19 may be inserted in a chuck 20 secured in a spring hammer or any other suitable device adapted to impart a reciprocatory motion to the shell. An aperture 21 is formed in the tongue 19 and aligned apertures 22 are formed in the chuck 20 so that the shell may be attached to the chuck by a pin or bolt (not shown) passed through the apertures 21 and 22 if the drill tends to stick in a hole when it is to be withdrawn therefrom.

Intermediate the ends of the shell 10 are provided a plurality of annular teeth 25 which have large diameters substantially equaling the largest diameter of the drilling 75 end of the shell. In the drilling operation the teeth 25 are adapted to assist the teeth 16 and 17 in removing material from the sides of the hole drilled into a ceiling 28 of concrete or drilled into any other wall or 80 article. This negates the necessity of allowing the clearance which is usually allowed on drill shanks and the like and insures that the shell will snugly fit the hole if it is subsequently expanded therein. The 85 shell 10 is preferably provided with a plurality of slots 30 forming weakened portions 31 adjacent the teeth 16 and 17 and forming passages whereby material removed from the bottom of the hole may pass from 90 the shell.

In practice, after the shell 10 has been employed to drill a substantially cylindrical hole 27 in a wall or an object, it is removed therefrom, and if it is to be secured in this hole, a tapered plug 33 is seated in its drilling end, the plug being preferably formed of case-hardened steel or the equivalent. The shell 10 is again driven in the hole 27 by any suitable means and during this second drill- 100

ing operation the plug 33 causes the drilling end of the shell to expand in the manner illustrated in Fig. 2, the weakened portions 31 being fractured. The teeth 25 and the teeth 16 and 17 enlarge the inner end of the hole 27 as indicated at 35 and the shell 10 becomes firmly fixed in the hole, as at the end of the second drilling each of the annular teeth 25 are imbedded in the wall of the hole and each forms a head of greater diameter than the diameter of the hole just back of it. As explained above, the shell 10 will snugly fit the hole throughout the entire length thereof. Another feature of my invention is that some of the material removed by the teeth 25 when the shell is driven into the hole for the second time packs in between the teeth 25 and wedges the shell in the hole.

After the shell 10 has been expanded and seated in the hole 27 the apparatus or article which is to be carried by the shell may be secured thereto by any suitable means. Obviously, any suitable coupling member (not shown) could be secured to the tongue 19 by passing a bolt (not shown) through the coupling member and through the aperture 21 in the tongue.

In the preferred embodiment of the invention, the teeth 16 are primarily designed to remove material from the bottom of the hole during the drilling operation and the teeth 17 are so designed that they crowd the material into the interior of the shell so that it may pass out through the slots 30. Of course, both the teeth 16 and the teeth 17 remove material from the sides of the hole.

It will be readily understood that the shell 10 can be employed to drill a plurality of holes 27. This will permit cheaper expansion shells to be driven into the holes to serve as anchor devices, the shell 10 being expanded in one of the holes when it becomes worn. The cheaper expansion shells may be of the type shown in my co-pending application Serial No. 33,775, filed May 29, 1925.

In a preferred embodiment of the invention, the tapered plug 33 is provided with a plurality of annular teeth 33^a so formed that they do not tend to seize and bite into the shell when the plug is driven thereinto, but so formed that they will resist withdrawal of the plug from the shell or withdrawal of the shell from the plug. This insures that the shell will remain firmly seated in the hole.

As hereinbefore set forth, both the shell and plug are preferably hardened, as this construction permits rapid driving of the shell into the hole and prevents the teeth 16 and 17 from biting into the plug. Hardening the shell throughout its entire length stiffens it and permits it to be used a maximum number of times as a drill, as well as insuring a minimum of distortion thereof during the initial drilling operation.

In Fig. 9, I have shown another form of

the invention embodied in a shell 10^a which is provided with drill teeth (not shown) substantially identical with the drill teeth 16 and 17 described above and is provided with annular teeth 25^a substantially identical with the aforementioned teeth 25. The shell is internally threaded as at 13 to receive a threaded rod or the like (not shown) whereby apparatus may be suspended from the shell. At its threaded end the shell is tapered as indicated at 14 to permit the shell to be seated in a chuck whereby the shell may be mounted in any suitable hammer device to drive the shell into concrete or the like, the shell being preferably rotated or oscillated during the drilling operation. Of course, the shell 10^a may also be employed to drill a plurality of holes and be expanded in one of them in the manner described above.

Shells embodying the invention may be formed from pipe, tubing, or plates, or may be cast if it is so preferred. In some instances, the shells may consist of a plurality of complementary sections embodying the invention.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A tubular anchor shell embodying drilling teeth at one of its ends, frangible members adjacent said end permitting expansion of said shell when broken, a chuck engaging portion at the other of its ends, means whereby cooperating parts may be attached directly to the shell after removal of the chuck, and cutting means intermediate the ends of the shell.

2. An expandible tubular anchor shell embodying drilling teeth at one of its ends, frangible means adjacent said end, an externally tapered portion at the other of its ends whereby it may be secured in a chuck, the tapered portion being provided with internal screw threads, and cutting means formed intermediate its ends.

3. An expandible tubular anchor shell embodying drilling teeth at one of its ends, frangible means adjacent said end, an externally tapered portion at the other of its ends, whereby it may be secured in a chuck, the tapered portion having means for operatively engaging apparatus to be carried by the shell, and annular cutting teeth formed intermediate its ends.

4. In an expandible anchor shell provided with drilling teeth at one end, frangible members adjacent said end, and chuck engaging means at the other end, and a plurality

of annular cutting teeth of equal diameters formed intermediate the ends of the shell.

5. A cylindrical anchoring device having a central bore therethrough and comprising drill teeth at one end thereof, frangible members adjacent said end and permitting expansion of said device when broken, said drill teeth having faces converging toward the longitudinal axis of the device to crowd 10 drilled material into said bore.

6. A cylindrical anchoring device having a central bore therethrough and comprising drill teeth at one end thereof, frangible members adjacent said end and permitting expansion of said device when broken, said drill 15 teeth each having faces converging toward the longitudinal axis of the device to crowd drilled material into said bore, and drill teeth interposed between the first-mentioned drill 20 teeth and differing therefrom in form.

In testimony whereof, I have hereunto signed my name.

JOHN H. PHILLIPS.
